(57) CLAIM

The ornamental design for a keel for a waterfowl decoy, as shown and described.

DESCRIPTION

FIG. 1 is a perspective view of a keel for a waterfowl decoy, showing a preferred embodiment of the new design.

FIG. 2 is a front elevational view of the keel for a waterfowl decoy of FIG. 1.

FIG. 3 is a first end elevational view of the keel for a waterfowl decoy of FIG. 1.

FIG. 4 is a second end elevational view of the keel for a waterfowl decoy of FIG. 1.

FIG. 5 is a top plan view of the keel for a waterfowl decoy of FIG. 1.

FIG. 6 is a bottom plan view of the keel for a waterfowl decoy of FIG. 1; and,

FIG. 7 is a rear elevational view of the keel for a waterfowl decoy of FIG. 1, but on a smaller scale and showing the keel attached to a waterfowl decoy.

The waterfowl decoy shown in broken lines in FIG. 7 is for illustrative purposes only and forms no part of the claimed design.
